UNITED STATES PATENT OFFICE

HORACE A. GOOLD, OF SOUTHGATE, CALIFORNIA, ASSIGNOR OF ONE-HALF TO MICHAEL L. FOGARTY, OF LOS ANGELES, CALIFORNIA

DRY CONCENTRATOR

Application filed April 4, 1930. Serial No. 441,613.

This invention relates to a concentrator for dry ores. The invention comprises an improved riffle construction which is combined with novel means for vibrating the riffle bed in such a manner as to cooperate efficiently with the peculiar construction of the riffles.

An object of the invention is to provide improved means for suddenly arresting the vibratory movement of the riffle bed in one direction thereby causing the lighter particles being treated to be directed towards the outlet for the tailings or gangue, in a more efficient manner, with the result that the heavier particles are more efficiently separated.

The invention further relates to a novel arrangement and construction of the riffles with relation to the riffle bed, whereby the more valuable concentrates are continuously fed to one side of the riffle bed in an improved manner, while the remainder of the concentrates are permitted to move toward the other side of the bed, thus making it possible to separate these two portions in a more satisfactory manner.

Other objects of the invention are to provide a more compact and efficiently operable device of the character described which can be transported conveniently upon pack mules or in any other manner necessary across rough country and which may more safely be depended upon to operate efficiently and without getting out of order.

Other objects, advantages and features of the invention may hereinafter appear.

Referring to the accompanying drawing which illustrates what is at present deemed to be a preferred embodiment of the invention,

Fig. 1 is a plan view of the riffle bed.

Fig. 2 is a side elevation of the riffle bed showing also the mechanism for vibrating the same.

Fig. 3 is an elevation looking at the left end of Fig. 1.

Fig. 4 is a cross section on line 4—4 of Fig. 1.

Fig. 5 is a cross section on line 5—5 of Fig. 1.

Fig. 6 is a cross section on line 6—6 of Fig. 1.

Fig. 7 is a diagrammatic plan of the riffle bed illustrating the surface contour thereof.

Fig. 8 is a side elevation of Fig. 7.

Fig. 9 is an elevation of the riffle bed looking at the small end thereof, and showing the same in a conventional manner on a reduced scale.

Referring in detail to the drawing, in order to provide means to support the riffle bed B, together with its riffles R, at the desired transverse inclination, said bed is mounted upon a deck or table T, to the bottom of which is secured the vertical portion 10 of the inverted T-rail member 11, the stem of said member being welded or otherwise secured to one arm of a hinge 13, the other arm of said hinge being secured, in any desired manner, to the bottom of the table T.

A plurality of stay bolts 17 which are arranged in pairs are provided, the members of each pair being aligned with each other and being adjustably connected by means of turnbuckles 18. The adjustment of these turnbuckles which connect one side of the table T with the plate 11, will regulate the transverse position of the table.

To the bottom of the part 11 is bolted or otherwise secured a downward extension or leg 25 having at its lower end a foot 26 which acts as a striker to strike a resilient bumper 27 carried by a standard 28 which is secured to the floor member 29.

Said leg 25, preferably at about its mid-length, is pivotally connected with the connecting rod 30 of the crank 31, which is driven by the crank shaft 32. Said crank shaft 32 has its bearings in a standard 33 mounted upon the top member 34 of the frame 35. Shaft 32 may be driven by a pulley 36 by

means of a belt 37 which passes over the driving pulley 38 of the motor 39.

In order to control the amount of rebound produced by the impact of the foot 26 with the resilient bumper 27, an inelastic flexible cable or connection 40 is secured at one end to said foot and at its other end, by means of an eye bolt 42, to the central portion of a leaf spring 43. The lower end of said spring is secured to the frame 35 by means of a clip 45, and the upper end of said spring is loosely held in place by means of a keeper 46. Nuts 47 and 48 on eye bolt 42 serve to adjust the length of the connection formed by cable 40 in conjunction with said eye bolt.

It will be observed that the leg 25 has directly connected therewith the means for oscillating the riffle bed and also has directly connected therewith the part which strikes the bumper 27 and the elements 40, 42 and 43 which partially arrest the movement of the riffle bed at the instant the striking element comes into contact with said bumper. This arrangement provides an improved device for withstanding the shock and also simplifies the construction of the machine, it being a simpler matter to connect the power for oscillating the riffle bed and the parts for restraining the oscillation thereof with a single part, such as the leg 25, than it would be to connect these features of the machine with different parts thereof.

The top member 34 of the frame 35 is preferably inclined to about the same extent as the riffle bed member B. Pillow blocks 50 are secured to the lower side of the plate 10, and the like pillow blocks 51 are attached to the frame member 34. These pillow blocks 50 and 51 are connected to each other by means of links 52 whereby the bed member B is operatively supported to be vibrated by the connecting rod 30.

Across the lower end of the riffle bed member B extends a discharge chute 60 wherein are provided upright gates 61 and 62, the gate 61 being pivotally supported at 61a at its lower end and the gate 62 being pivotally supported at 62a at its lower end. These gates form adjustable partitions of the well known kind to direct the discharge material through the discharge openings 63, 64 and 65.

The valuable materials which are directed by the riffles R toward the lower side of the riffle bed as viewed in Fig. 1, are all collected at the lower left hand corner of said riffle bed by means of a substantially horizontal metal plate 70 provided with one or more creases 71, said crease or creases serving to conduct the valuable material into the discharge hopper 65. Therefore the shape of the riffles R combined with the way that the bed is vibrated begins to separate the fine values from the coarse at the commencement of this travel over the riffle bed, and the construction of the riffles on the lower end of

the table separates the coarse values from the coarse gangue, and the fine values and the coarse values meet at one corner of the lower end of the table.

The riffle bed B tapers throughout its length uniformly on each side. On the feed end the surface is higher, say one inch above the level of its other end. The material to be treated is fed to the riffle bed near the right hand end thereof as viewed in Fig. 1. It may be either mechanically or manually supplied, and should in either case be delivered to the portion marked "Low point" in Fig. 7.

The riffles are so constructed that they rise from the center of the table on the concentrate side allowing the coarse to flow over the fine as the result of the oscillation of the riffle bed. On the tailing side of the feed end the riffles are so raised that they are higher till they reach the center of the table on the side thereof that forms a pocket down through the center of the table allowing the values to be separated from the gangue as its flows down across the center of the table, being forced by the movement of the table toward the concentrate side.

In Fig. 7 is diagrammatically indicated the preferred surface slope and levels of the upper surface of the riffle bed member B whereby the course taken by the materials moving across said bed is controlled as desired. In this view the part labeled "high level" is substantially flat and substantially parallel to the general plane of the upper surface of the riffle bed.

The triangular surface 75 at the right hand side of said high level area slopes down to the corner portion labeled "Low point". At the other side of the high level area is the other sloping area 76 which slopes from the high level side down to the corner portion labeled "Low point" at the side of the view.

Describing in detail the construction of the riffles, upon the riffle bed B is mounted a series of transversely extending cross bars C upon which are supported the series of riffles R which extend diagonally with respect to the riffle bed. Each of these riffles, by preference and as shown, is of the same width and throughout the greater portion of its length is the same height. Adjacent one side of the riffle bed as a whole and throughout the entire length thereof said riffles R are each provided with the risers 82 which are illustrated in detail in Figs. 4 and 5. These risers 82 consist of wedge shaped bodies which are bevelled in two directions that is to say are not only bevelled with regard to their length but are bevelled from side to side so that their thin ends, which are directed toward the feed or intake end, terminate not in a line, but practically in a single point.

The preferred arrangement of these risers is such that, for example, in a riffle bed eight feet in length, throughout the upper four feet

of the length of the riffle bed these risers will each come up to the top of the riffle in which it is located; but throughout the remaining lower portion of the riffle bed they will gradually become lower until they produce very little effect on the substance passing thereover.

Each of said risers are provided at the side thereof which is directed toward the discharge end of the riffle bed, with a groove 83 adapted to conduct any of the light fine values across to the next lower riffle.

Laterally beyond the area of the riffle bed which is provided with these risers, the riffles 15 may all be left unobstructed, as shown in the drawing, but the invention is not limited to the use of these risers in any particular part of the riffle bed.

Distributed, preferably throughout the entire floor of the riffle bed, are a series of tongue members 90, one of which is shown in detail in Fig. 6. These tongue members are struck up from the sheet metal plate P which forms the bottom of the riffle, each of said members 25 having its free end directed downwardly that is, toward the discharge end of the riffle bed. This provides a transverse groove 91 along the upper side of the tongue 90 and a slit 92 toward its free end, this arrangement aids in 30 separating the values.

Air is taken in through the bottom of the table adjacent the discharge end, by means of the air inlet member 97, thus passing up through the slots 92 and lifting the material, 35 thus helping in the separation of light and heavy and of small and coarse values from the gangue.

The sheet metal tongues 90 can be bent at will to regulate the side of the slits 94 at their 40 sides and the slits 92 at their ends, thus regulating the flow of air through the bottoms of the riffles.

In Fig. 2 the length of the crank arm 31 is 45 exaggerated for clearance of illustration. In practice the distance which the riffle bed will be vibrated will vary from a quarter of an inch to three quarters of an inch.

During the oscillation of the riffle bed the fine values are forced to the bottom of the 50 riffles. While the ore is passing over the face of each riser the coarse values are always on the up-grade side of the riser.

The groove 83 reaches to the lower side of 55 the riser at the pointed end of said riser. Therefore every time a portion of ore passes across the riser, the riser performs a partial cleaning, by removing a portion of the gangue.

60 The groove 83 prevents any values that happen to climb up the riser from being carried over with the gangue into the next riffle.

The whole tendency of the risers is to keep 65 the fine values above the coarse on the surface of the risers or riffles until such fine values are

discharged into the hopper for the concentrates at the end.

If any of the coarse values are caught in the middling hopper 64, they can be reground and the fines extracted from them by 70 returning them across the table.

I claim:

1. In combination, a riffle bed, a resilient bumper, means for supporting said bumper in a fixed position adjacent to said bed, a 75 rigid extension carried by said bed and adapted to strike said bumper, an inelastic connection adjustably connected with said extension to limit the extent to which said extension moves against said bumper, a rod connected with said extension, means to reciprocate said rod to vibrate said bed, and a leaf spring to which said connection is secured.

2. In combination, a riffle bed, a resilient bumper, means for supporting said bumper in a fixed position adjacent to said bed, a rigid extension carried by said bed and adapted to strike said bumper, an inelastic connection adjustably connected with said 80 extension to limit the extent to which said extension moves against said bumper, a rod connected with said extension, means to reciprocate said rod to vibrate said bed, and a leaf spring supported at its ends, said connection being secured to said spring between 85 its ends.

3. In combination, a riffle bed, a resilient bumper, means for supporting said bumper in a fixed position below said bed, a leg rigidly 100 fixed to said bed and provided with a striking portion to strike said bumper, resilient means connected with the striking portion of said leg to oppose its movement as it comes into engagement with the bumper, and means connected with said leg between the striking portion thereof and the riffle bed to oscillate 105 said leg and the riffle bed.

4. In combination, a riffle bed, a resilient bumper to oppose the movement of said bed in one direction, a flexible connection operatively related to said bed to limit the extent to which said extension moves against said bumper, a spring to which said flexible connection is attached, means to adjust the 110 length of said connection with relation to said spring, and means to vibrate said bed.

5. A riffle provided with a riser of a wedge shape tapered in two directions, the thick side of said riser being positioned along one 115 side of one of the riffle walls to discharge the gangue into the next riffle, said riser having a longitudinal groove adjacent the next riffle to discharge values over the front end of the riser, thereby preventing said values 120 from passing into the next riffle with the gangue.

6. A riffle provided with a riser of a wedge shape tapered in two directions, the thick side of said riser being positioned along one 125 130

side of one of the riffle walls to discharge the gangue into the next riffle, said riser having a longitudinal groove adjacent the next riffle to discharge values over the front end of the riser, thereby preventing said values from passing into the next riffle with the gangue, said groove extending from the top of said riser to the lower side and pointed end thereof.

10 In testimony whereof I hereunto affix my signature.
